SUCTION CLEANER

Filed Nov. 24, 1943

UNITED STATES PATENT OFFICE

2,404,244

SUCTION CLEANER

Joseph H. Nuffer, Toledo, Ohio, and Lynn H. Latta, Los Angeles, Calif., assignors to Air-Way Electric Appliance Corporation, Toledo, Ohio, a corporation of Delaware

Application November 24, 1943, Serial No. 511,525

2 Claims. (Cl. 230—133)

1

This invention relates to suction cleaners of the type in which the filtering and suction units are both enclosed within a rigid housing through which a dust laden air stream is lead through a flexible suction hose from a cleaning tool.

An object of the invention is to produce a suction cleaner of this type wherein the filtering unit is vertically disposed and the hose is connected to the housing in such a position as to attain maximum efficiency in the conveyance of a dust laden air stream to the filtering and collecting units, and yet the center of gravity of the entire body of the cleaner is sufficiently low and the weight is sufficiently distributed horizontally so that the cleaner body may be dragged about by the suction hose without being tipped over by the pull of the hose.

Another object of the invention is to provide a cleaner wherein the space within a streamlined housing, such as, for example "a tear drop" shape, is utilized so as to obtain maximum compactness.

The present invention is directed particularly to the problem of converting a cleaner of the type above indicated, into a blowing device, and has as a particular object to produce an arrangement wherein the insertion of a hose coupling to a blower outlet will automatically close the normal discharge aperture of the fan and provide for the concentration of the discharge at the blower outlet.

A further object is to produce, in a vacuum cleaner of the type indicated, a suction unit having a normally diffused, sound muffled outlet and having means whereby this normal outlet can be closed and the discharge concentrated for delivery to a blower attachment, and wherein this conversion may be made simply by inserting the blower attachment hose connection into the blower outlet of the cleaner.

A still further object of the invention is to provide a vacuum cleaner with a blower outlet having a closure member which is self-closing and which is adapted to be opened by the pressure of a blower connection thereagainst.

Other objects and advantages of the invention will hereinafter appear, and for purposes of illustration but not of limitation, an embodiment of the invention is shown in the accompanying drawing, in which

Figure 1 is a longitudinal sectional view of a vacuum cleaner embodying the invention;

Figure 2 is a partial sectional view showing the blower coupling connected to the discharge of the suction unit;

Figure 3 is a plan view of the blower outlet; Figure 4 is a side elevation of the cleaner; and Figure 5 is a fragmentary sectional view showing the valve disc in open position.

5 As an example of one form in which the invention may be embodied, we have shown in the drawing the body portion of a suction cleaner embodying a suction unit 10 and filtering unit 12 mounted side by side upon a base 14. A cover 16 cooperates with the base 14 to form a housing defining a chamber 17 in which the suction and filtering units 10 and 12 are enclosed. The cover 16 is hinged to the base 14 by means of a hinge 18. The base 14 has an upwardly offset portion 15 22 and a raised portion 24 extending rearwardly from the offset portion 22, the hinge 18 being formed at the rear end of the raised portion 24. The cover is held in its closed position by latches 26, one on either side thereof, and has at its lower 20 rear extremity a tail portion 28 extending below the hinge 18 and adapted, when the cover is raised to an upstanding position, to engage the under side of the raised portion 24 of the base so as to support the cover in such upstanding position.

25 When the cover is thus raised to an upstanding position, the suction unit 10 and filtering unit 12 will be substantially completely exposed above the base 14 for servicing operations as, for example, removal and replacement of the carbon brushes 30 of the suction unit 10, or removal of the screws 32 by means of which the suction unit 10 is attached to supporting brackets 34 or 35.

The filtering unit 12 includes a receptacle 20, 30 a perforated liner 36 encircling and supporting the lateral wall of the receptacle 20, and a tubular casing 38 encircling and spaced from the liner 36. At the upper end of the casing 38 is an annular channel 40 in which is mounted a packing ring 42 of compressible material such as, for example, soft rubber, and the receptacle 20, which is preferably of porous paper so that it may be disposed of when filled, is provided at its upper end with a non-porous flange 44 resting upon the packing ring 42.

The cover 16 is formed with an annular clamping flange 46 adapted to clamp the flange 44 against the packing ring 42, and with a delivery nozzle 48 receivable in a central opening 50 in a non-porous top member 52 which is secured to the receptacle 20. The top member 52 may be connected integrally with the flange 44 by an offset portion 54 by means of which the top member is stitched to the receptacle 20. The nozzle 48 carries a sealing ring 56 of compressible ma-

terial, such as soft rubber, which is adapted to seal the nozzle to the top 52. The parts are so arranged that the sealing of the nozzle 48 to the top 52 and the clamping of the flange 44 against the packing ring 42 is effected by moving the cover 16 to a closed position and latching it in that position. Conversely, the raising of the cover 16 to the vertical position uncovers the filtering unit so that a filled receptacle 20 may be removed and replaced by a fresh receptacle.

Formed in the cover 16 is an inlet 58 which is connected to the nozzle 48 by a short duct 60. A cleaning tool (not shown) is adapted to be connected to the filtering unit 12 by a flexible suction tube 66 having on one end a suitable connector swivel to permit swiveling of the tube 66 relative to the body of the cleaner. Suitable means, such as a latch 69 may be employed for connecting the hose to the inlet 58 in such manner as to form a draft connection by means of which the cleaner body may be pulled around at the end of the tube 66.

The casing 38 of the filtering unit 12 is mounted at its lower end on an annular flange 70 formed integrally with the base 14 and constituting one end of a duct 72 adapted to apply suction to the lower end of the casing 38, which is open and in communication with an annular port defined by the flange 70. Suitable attaching elements such as screws 62, extending upwardly through the base 14 and flange 70 and threaded into an inturned flange 64 on the lower end of the casing 38, may be employed for securing the casing 38 to the flange 70. The other end of the duct 72 is extended diagonally upwardly and rearwardly as at 73, and mounted in the duct portion 73 is a short length of tubing 74 of yieldable material, such as soft rubber.

The suction unit 10 includes an electric motor having a casing 78 to one end of which is attached the fan casing 84. The other end of the motor casing 78 is provided with an inlet 76 to which the flexible tube 74 is connected as shown. Encircling and secured to the casing 78 is an annular vibration absorbing mounting 80, which is attached to the brackets 34 and 35 by the screws 32 as previously stated, and which thus forms the means for mounting the suction unit upon the base 14, the bracket 34 being secured directly to the base 14 and the bracket 35 being secured to one side of the filter unit casing 38. The suction unit 10 is adapted to vibrate about the center of the mounting 80, with the soft rubber tube 74 permitting the lower end of the motor casing 78 to vibrate without transmitting such vibrations to the base 14.

The suction unit 10 is arranged on an axis which is inclined upwardly and rearwardly from the duct portion 73. An important advantage of this arrangement lies in the fact that it provides for maximum closeness of coupling between the inlet 76 of the suction unit and the open lower end of the filter casing 38, thus increasing the suction efficiency of the cleaner. A further advantage of the arrangement arises from the disposition of the fan housing 84 at such an angle as to make available for it a space of maximum extent in the plane of its radii. This provides the necessary space for accommodating the shroud and discharge valve mechanism which will now be described.

The fan housing 84 is in the form of two stampings secured together by annular flange means 85. In the outer stamping is a series of discharge openings 86. From the openings 86 the air is

normally discharged through a sound muffling hood 87 into a chamber 88 defined within a shroud 89. The shroud 89 has an inturned flange 90 secured to the flange 85 of the fan housing, and an outturned flange 91 to which is secured an annular valve seat 92 of soft rubber or the like. Between the valve seat 92 and the flange 91 is secured a screen 93 of wire cloth or perforated metal. The valve seat 92 is vulcanized to the flange 91 and secures the screen 93 in place.

Mounted in the flange 91 and projecting through the valve seat 92 is a series of pins 94. A valve disc 95 has a plurality of apertures freely receiving the pins 94. Thus the valve disc is mounted for bodily movement toward and away from the valve seat 92 while supported for sliding movement on the pins 94. A plurality of light coil springs 96, mounted on the pins 94, are interposed between the valve disc 95 and the seat 92 and serve normally to maintain the valve disc 95 spaced away from the seat 92 so as to provide an annular discharge opening through which the exhaust from the suction unit 10 may be discharged in all directions. The screen 93 supports the muffling hood 87 against being distended into contact with the valve disc 95. The air noises produced by the passage of the discharge through the openings 86 is muffled as the air passes through the hood 87 and is further muffled by a dispersal of the discharge in all directions in a thin flat stream through the annular discharge aperture between the valve disc 95 and the seat 92.

In the center of the valve disc 95 is a neck member 97 which is adapted to receive a blower and coupling member 68a on the end of the hose member 66a. The coupling 68a may be provided with a latch element 69a adapted to cooperate with a discharge outlet 98 in the cover 16 so as to hold the coupling 68a securely in contact with the neck member 97, with the valve disc 95 held snugly against the valve seat 92.

It may now be noted that the insertion of the coupling 68a through the blower outlet 98 and the pushing of the coupling snugly against the neck member 97, serves to close the normal discharge opening and to concentrate the fan discharge at the blower coupling. In addition, the insertion of the coupling serves to open a plurality of segment shaped closure members 99 which are hinged as at 100 to the casing 16 around the periphery of the blower outlet 98, the enclosure members 99 being simply pushed aside by the coupling 68a as it is pushed through the blower outlet 98. The closure members 99 are returned to their closed position shown in Figures 1 and 3 by means of light spring members 101.

It is to be understood that numerous changes in details of construction, arrangement and operation may be effected without departing from the spirit of the invention especially as defined in the appended claims.

What we claim is:

1. In a suction cleaner, a housing having a blower outlet, a suction unit in said housing having a fan casing provided with a normal discharge aperture, a shroud providing a discharge chamber into which said aperture discharges, an outturned peripheral seating ledge on said shroud, a substantially flat valve disc providing the outer wall for said shroud and adapted to seat against said ledge, and resilient means interposed between said disc and ledge normally maintaining a spaced relation between said valve disc and said seating ledge, said disc having a blower discharge

5.

opening aligned with said blower outlet, whereby said suction unit normally discharges through said blower discharge opening and the space between said valve disc and said seating ledge, said blower outlet being adapted to receive a blower attachment coupling extended therethrough and into contact with said valve disc for moving said disc into sealing engagement with said ledge.

6

2. In a suction cleaner as claimed in claim 1, wherein said resilient means comprises spring elements interposed between said ledge and said valve disc, and pins serving as guides for the movement of said disc.
